UNITED STATES PATENT OFFICE.

AUGUST J. ENGELMANN, OF ST. LOUIS, MISSOURI.

MUSICAL INSTRUMENT OF THE ACCORDION TYPE.

No. 884,373.

Specification of Letters Patent.

Patented April 14, 1908.

Application filed June 18, 1907. Serial No. 379,652.

To all whom it may concern:

Be it known that I, AUGUST J. ENGELMANN, a citizen of the United States, and resident of St. Louis, Missouri, have invented certain new and useful Improvements in Musical Instruments of the Accordion Type, of which the following is a specification.

This invention relates to improvements in musical instruments of the accordion type, and consists in the novel arrangement, construction, and combination of parts as will be fully hereinafter described and claimed.

The object of my invention is the construction and formation of the spring whereby the valves of the instrument are controlled and held in closed position when not in use.

The essential feature of my invention is the spring.

In the drawings; Figure 1 is a top plan view of the valve end of an accordion with parts broken away showing the arrangement of valves in relation to the spring. Fig. 2 is a central cross-sectional view of the same taken on the line 2—2 of Fig. 1. Fig. 3 is a detail perspective view of my improved spring.

In the construction of my invention I provide a sheet of spring material 4 suitably cut and stamped forming a plurality of prongs 5, the ends of said prongs suitably bent forming a recess 6 in which are adapted to rest the ends 7 of the valve stem 8.

The base of the spring or that part from which the prongs are formed is provided with openings 9 for the insertion of screws by which the spring is securely fastened to the casing 10 of the accordion frame, and the base portion is suitably strengthened by an integral upturned flange or strengthening rib 10'.

I will now describe the construction of the valve mechanism which is in combination with and controlled by my improved spring.

11 indicates a hollow key frame into which project a plurality of key bars 12, its ends provided with keys or finger knobs 13 which project through openings 14 in the side of the frame. While playing the instrument the fingers are brought in contact with the buttons 13 and when pressed inwardly in the position as shown by dotted lines in Fig. 2, they will raise the valves 15 upwardly permitting the air to pass outwardly and create the tone by coming in contact with the reed

of the instrument. The key bars 12 are pivotally secured in the bottom of the frame 55 upon a rod 16.

The valve 15 is secured upon the valve stem 8, and the said valve stem projects through the lower end of the key bars, and its end referred to by the numeral 7 is extended through the frame sufficiently to contact with the ends of the prongs 5.

The spring is covered by a casing 17 and held in position upon the frame by the screws 18 (see Figs. 1 and 2). The valves are also 65 incased in a casing 19 which is supported to the frame by the screws 20. The essential feature of my invention is the construction of the spring formed out of a single sheet so that the prongs may be at all times in proper 70 relation with the valve stem, and the same can be readily and easily placed in position upon the casing, and its ends contacting with the projecting end of each valve stem. If desired I may construct each prong separately and arrange them in alinement upon 75 the casing in the same position as the integral formation of the spring.

Heretofore the springs used in connection with the valves of an accordion have been of 80 the coil spring nature, and from my experience in the musical business I have never found a leaf spring used in this connection.

Having fully described my invention, what I claim is:

1. A musical instrument comprising a spring formed of a single sheet in combination with valve stems and valves, said spring having a plurality of integral prongs so bent and shaped as to contact with the projecting 90 ends of the valve stems to retain the valves in closed position, and a strengthening rib on the spring, substantially as specified.

2. A musical instrument comprising an accordion provided with a casing, a spring 95 in combination with valve stems and valves, said spring being formed of a single sheet, said spring having a plurality of projecting integral prongs contacting with the valve stems, means for retaining said spring in position upon the casing of the accordion, a strengthening rib on the spring, and a cover inclosing the spring, substantially as specified.

3. A musical instrument comprising an 105 accordion provided with a casing, a spring

having a plurality of integral projecting prongs, and a base portion, a strengthening rib on the spring, valves mounted in the casting of the accordion and valve stems where-
5 by said valves are actuated, substantially as specified.

In testimony whereof, I have signed my

name to this specification, in presence of two
subscribing witnesses.

AUGUST J. ENGELMANN.
